UNITED STATES PATENT OFFICE.

ALBERT G. SCHERER, OF CHICAGO, ILLINOIS, ASSIGNOR TO EXCELSIOR STEEL FURNACE COMPANY, OF CHICAGO, ILLINOIS, A CORPORATION OF ILLINOIS.

FURNACE.

1,224,220.

Specification of Letters Patent.

Patented May 1, 1917.

Application filed January 14, 1916. Serial No. 72,029.

To all whom it may concern:

Be it known that I, ALBERT G. SCHERER, a citizen of the United States, and a resident of the city of Chicago, county of Cook, and 5 State of Illinois, have invented certain new and useful Improvements in Furnaces, of which the following is a specification.

My invention relates to the type of heating apparatus known as "pipeless furnace," 10 wherein the register opening is divided and the separate parts connect respectively with the pipes supplying the heater with air and with the heated air discharge channels so that a draft of air is conducted through a 15 casing or shell surrounding the furnace body for the purpose of heating the same to a proper temperature and then discharging it through a register in the floor of the room or other apartment immediately below 20 which the apparatus is preferably installed.

The principal object of my invention is to secure a material economy, both in the size of the furnace and in the materials necessary for manufacturing the same. Here- 25 tofore, so far as I am aware, furnaces of this type have all had an outer casing, be- 30 tween which and the usual casing the air supply was conducted to the bottom of the furnace, entirely surrounding the usual fur- 35 nace casing. This construction has resulted in an extremely bulky structure, difficult to 40 install, and expensive to make. With my present design I believe I have secured a furnace the efficiency of which is in no way 45 impaired or lessened, which requires hardly 50 more room for installation than the single casing furnace, and requires a materially less amount of metal to fabricate. Another 55 object is the provision of suitable means 60 whereby the apparatus may be adjusted in 65 height to accommodate itself to cellars or 70 furnace rooms of divers heights. Still an- 75 other object is to so construct and dispose 80 the elements of the apparatus that the reg- 85 ister may be covered during any period 90 when the furnace is not in operation, thereby 95 eliminating the unsightly appearance of 100 the floor of the room or other apartment 105 wherein the same is installed and prevent- 110 ing the register opening becoming a place 115 for the reception of dirt, dust and vermin. A further object of my invention is to pro- 120 vide a furnace with suitable draft conduits 125 whereby an efficient circulation of air is 130 obtained therein for the purpose of heating

the same. A further object is the provision of a unitary heating apparatus that is effective in its operation, and is simply and inexpensively constructed so that it is easy to operate and does not materially add to 140 the cost to the user.

I prefer to accomplish the divers objects of my invention by the means and in the manner hereinafter fully described and as more particularly pointed out in the claims, 145 reference being had to the accompanying drawings forming a part of this specification and wherein similar reference characters are employed to indicate the same parts throughout the various views. 150

In the drawings,—

Figure 1 is a view, the right-hand portion 155 whereof is a vertical front elevation of my improved heating apparatus, and the left- 160 hand portion whereof is a transverse ver- 165 tical section thereof taken through the outer 170 casing and cold air conduit. 175

Fig. 2 is a transverse horizontal section 180 taken on line 2—2, of Fig. 1, looking in the direction of the arrows. 185

Fig. 3 is a fragmentary detail, drawn in 190 section, showing the manner of lowering and covering the register when the appa- 195 ratus is not in operation. 200

Fig. 4 is a sectional detail showing the 205 manner of joining the air supply conduits 210 to the furnace shell or casing. 215

Referring to the drawings, and more par- 220 ticularly to Fig. 1, it will be observed that 225 the furnace is of an ordinary commercial 230 type, comprising the usual fire dome, 10, fire 235 pot, 11, and ash pit, 12, superimposed the 240 one upon the other and provided with the 245 usual openings for charging the fuel, the 250 removal of ashes and the regulation and 255 admission of draft thereto. Upon the top of 260 the fire dome, 10, is disposed a cylindrical 265 or drumlike radiator, 13, into which the 270 heated products of combustion pass from 275 said dome and out from which they are dis- 280 charged to the chimney or smoke flue (not 285 shown). Surrounding the heater is a shell 290 or casing of substantially cylindrical shape 295 the top of which is divided into a central 300 compartment for the discharge of hot air 305 and an outer chamber concentric with the 310 central chamber for the admission of air to 315 the heating surfaces. This casing extends 320 up toward the register disposed in the floor 325 of the room, and both of said chambers have 330

their walls telescopically engaging the lower end portions of a double-wall register box depending from the register. This casing or shell preferably comprises a cylindrical 5 basal section, 14, a similarly shaped intermediate section, 15, mounted upon an interposed bracing ring, 16, and a cylindrical top section, 25, near the base of which is provided an inwardly extending bead, 31. Resting upon and extending upwardly from the bead, 31, is a tapered or conical shaped section, 17, the upper portion whereof assembles with a vertically disposed cylindrical head, 18, of considerably less diameter than 10 the lower or body portions of the casing.

The floor, 19, of the room or other apartment it is desired to heat is provided with an opening, of substantially rectangular shape and surrounded by headers, 20, for the 20 purposes to be hereinafter described. The register, 21, is of any convenient construction, preferably rectangular in shape so as to fit the opening formed by the headers and is perforated or grilled to permit the passage 25 of air therethrough. The register box preferably comprises an inner sleeve, 22, secured centrally to the under surface of the register, 21, and depends therefrom a distance sufficient to permit of a sliding engagement 30 or telescopic fit of the same with the upper portion, 18, of the casing, it, of course, being understood that the sleeve, 22, is of either a slightly less or a greater diameter than the said member, 18, so as to 35 permit of the aforesaid adjustment and fit.

The outer wall of the box is disposed a distance away from the inner wall and provides a concentric chamber around the same, down through which the cold air from the 40 room will pass.

The lower portion of the basal member, 14, of the casing is provided with air openings, 22, through which the cooler air, which gravitates through the register is admitted 45 into the casing and is there heated so that it ascends and circulates around the furnace and its radiator and discharges through the central portion of the register, 21.

Mounted vertically upon the exterior of 50 the casing are suitable elongated conduits or cold air flues, 23, the lower portions whereof surround the openings, 22, above mentioned and the upper portions whereof are inclined inwardly as at 24, where they 55 are secured to the top section, 25. The conduits, 23, are substantially U-shape in cross-section and consist of sides, 32, connected by a wall, 33. The free edges of the walls are adapted to enter channels, 34, formed by 60 suitably bending a plate, 35, which is secured to the furnace by rivets or in any other suitable manner. The tops of the conduits, 23, are preferably riveted at 36 to the furnace casing, while the bottoms of said 65 conduits are secured to the casing by straps,

37. The wall of the section, 25, is provided with openings, 26, communicating with the conduits, 23, and its upper edge is seamed or otherwise secured to an upwardly and inwardly inclined shell, 27. The upper portion, 28, of this shell, 27, terminates approximately in the horizontal plane with the upper edge of the cylindrical member, 18, of the casing and telescopically fits the lower cylindrical end, 29, of the outer wall, 30, of the register box. This construction permits the cold air which gravitates to the floor of the room or apartment above the furnace to pass downwardly through the outer concentric chamber or passage, through the openings, 26, into the conduits, 23, and thence through openings, 22, into the interior of the furnace casing, where, upon being heated, it ascends around the furnace body and discharges through the central chamber 35 of the furnace casing.

As heretofore mentioned, the register, 21, is adapted to be moved out of the way when the furnace is not in operation and in order to do this I prefer to form rabbets, 41, upon 90 the upper inner corners of the headers, 20. Suitable filler strips, 42, of less height than the distance from the bottom of the rabbet to the plane of the floor, are movably mounted upon the headers and fitted into the rabbets by means of hinges, 43. The register, 21, is placed upon the upper edges of the filler strips, 42, when the furnace is in operation, but when it is desired to shut down the furnace the register is raised and the 95 filler strips, 42, dropped so that the rabbet is free to support the register upon its lowermost surface. After this has been done, a section of flooring or a suitable door, 44, may be placed upon the top of the register 100 so that the upper surface of the floor will lie flush with the remaining portion of the floor of the room, substantially as shown in Fig. 3 of the drawings, and thereby exclude 105 dust and dirt from the register opening.

In order that access may be had to the interiors of the conduits, 23, for the purpose of permitting the mechanic to assemble said conduits with the casing, I have provided suitable hand holes, 45, in the inclined 110 upper walls of said conduit and the same are closed by a door or plate, 46, removably fitted over said opening.

What I claim as new is:—

1. Heating apparatus comprising a heating element, a casing surrounding the same and spaced therefrom, the upper portion of said casing being tapered inwardly and extended upwardly to provide a conduit for the air heated by said heating element, an auxiliary shell surrounding the tapered and upwardly extending portion of said casing and disposed concentrically therewith, a pair of channeled members disposed longitudinally of said casing, and a U-shape conduit 120

member mounted in the channels of said members and establishing communication between the interior of said casing and shell.

2. Heating apparatus comprising a heating element, a casing surrounding the same and spaced therefrom, the upper portion of said casing being tapered inwardly and extended upwardly to provide a conduit for the air heated by said heating element, an auxiliary shell surrounding the tapered and upwardly extending portion of said casing and disposed concentrically therewith, a pair of channeled members disposed longitudinally of said casing, a U-shape conduit member mounted in the channels of said members and establishing communication between the interior of said casing and shell, and a register box formed with inner and outer walls adapted to respectively tele-

scopically engage the upwardly extending portions of said casing and shell.

3. Heating apparatus comprising a heating element, a casing surrounding the same and spaced therefrom, the upper portion of said casing being tapered inwardly and extended upwardly to provide a conduit for the air heated by said heating element, an auxiliary shell surrounding the tapered and upwardly extending portion of said casing and disposed concentrically therewith, a pair of channeled members disposed longitudinally of said casing, a U-shape conduit member mounted in the channels of said members and establishing communication between the interior of said casing and shell, and a register having depending therefrom a register box formed with inner and outer walls adapted to respectively tele-

scopically engage the upwardly extending portions of said casing and shell.

4. Heating apparatus comprising a heat-

ing element, a casing surrounding the same and spaced therefrom, the upper portion of said casing being tapered inwardly and extended upwardly to provide a conduit for the air heated by said heating element, an auxiliary shell surrounding the tapered and upwardly extending portion of said casing and disposed concentrically therewith, a pair of members having longitudinal grooves therein and disposed vertically upon said casing, and a U-shape conduit member the edges whereof are adapted to enter the grooves in said members and form a conduit with said casing for establishing communication between the bottom of said casing and the compartment formed by said casing and shell.

5. A furnace, a shell therefor, a register connecting with said shell, means for supporting said register comprising headers each provided with a rabbet upon its upper inner edge, a hinged strip disposed in each of said rabbets and adapted to swing out of and below the same, said register being normally supported by said strips and adapted to rest on said rabbets with said strips in lowered position, and a cover above said register.

6. A heating unit, a shell inclosing same, a register communicating with said shell, and means supporting said register comprising a frame peripherally rabbeted upon its inner edge, and members removably disposed in said rabbets upon which said register rests.

Signed at Chicago, county of Cook and State of Illinois, this 28th day of Dec., 1915.

ALBERT G. SCHERER.
